United States Patent Office.

SAMUEL A. BLAKE, OF MILFORD, CONNECTICUT.

Design No. 3,097, dated July 14, 1868.

DESIGN FOR IMITATION-BRAID FOR BONNETS.

The Schedule referred to in these Letters Patent and making part of the same.

TO ALL WHOM IT MAY CONCERN:

Be it known that I, SAMUEL A. BLAKE, of Milford, in the county of New Haven, and State of Connecticut, have invented a new Design for Imitation-Braid for Bonnets, &c.; and I do hereby declare the following, when taken in connection with the accompanying drawing, to be a full, clear, and exact description of the same, and which said drawing constitutes part of this specification, and represents a piece of fabric embossed in accordance with the design.

This invention relates to a design for imitation of straw braid, representing a sewed braid.

The design is fully and clearly shown in the accompanying illustration; and

What I claim as my design is—

The design for imitation of straw braid, as herein fully illustrated and described.

S. A. BLAKE.
